GOLF BAG SUPPORT

Frank J. Hearnshaw, Chicago, Ill.

Application June 29, 1939, Serial No. 281,793

2 Claims. (Cl. 248—96)

This invention relates to a golf bag support, and the primary object of the invention is to provide means attachable to a golf bag to support the golf bag in upright position and to prevent the same from tipping over.

A further object of the invention is to provide a support for a golf bag whereby means are provided concealed underneath the base and adapted to be moved outwardly from the base to provide a stand to support the golf bag in upright position and prevent the bag from falling over.

Another object of the invention is to provide a golf bag support or stand for supporting a golf bag in upright position, there being a plurality of pivotally mounted members which are swung underneath the support in nesting relationship when the bag is being carried or when not in use, and which may be swung outwardly on their pivots to provide a stand or support of substantial area to maintain the bag in upright position.

Another object of the invention is to provide means for supporting a golf bag so that a golfer who acts as his own caddy may carry the bag between shots in the usual way, but when arriving at the ball may spread out feet or supports to maintain the bag in a proper upright position, thereby avoiding the necessity of laying the bag on the ground which naturally scars and mars the clubs, and also making it impossible for rodents and reptiles to crawl into the bag.

A still further object of the invention is the provision of a new and novel golf bag base having improved means formed thereon which are normally concealed underneath the base and which are adapted to be projected outwardly from the base to provide a support or stand of sufficient area to maintain the golf bag in an upright position.

Numerous other objects and advantages will be apparent throughout the progress of the following specification.

The accompanying drawing illustrates a selected embodiment of the invention and the views therein are as follows:

Fig. 1 is a detail elevational view of a golf bag and embodying the invention;

Fig. 2 is a transverse sectional view on the line 2—2 of Fig. 1;

Fig. 3 is a view similar to Fig. 2 but showing the wings in extended or supporting position; and

Fig. 4 is a detail sectional view on the line 4—4 of Fig. 2.

The particular golf bag construction herein shown for the purpose of illustrating the inven-

tion comprises a golf bag having a tubular body portion 10 which may be made of leather, fabric, or any other conventional material. The body 10 is tubular in shape and while shown elongated, the invention is just as applicable to conventional circular or round bags. The tubular body portion 10 is adapted to be fastened to a supporting base 11 which comprises an upstanding continuous flange or ring 12 into which the tubular body 10 is fitted. Rivets or other fastening means 13 fixedly connect the body 10 to the supporting base 11. The base 11 may be made of any durable material, such as fabric, metal or any other kind of material capable of performing the function intended. The rim or flange 12 may be relatively flush with the exterior of the bottom portion of the base member 11, or it may be set inwardly a predetermined distance, as clearly shown in Figs. 2 to 4.

20 Wings or flaps 14 and 15 are fixedly but pivotally connected to the flange 16 which extends outwardly from the rim or upstanding flange 12. The wings 14 and 15 comprise body portions 17 and 18, respectively, and each wing is provided 25 with a circular boss or bearing portion 19 and receives a pin 20 which is also received in the flange 16. Each pin 20 may have a head 21, Fig. 4, which is countersunk in the thickened or boss portion 19. The body of the pin may have a drive fit with the extending rim 16 or it may be provided with a head portion 22, Fig. 4, so that each wing 14 or 15 may be pivotally mounted to the base 11 and permit free pivotal movement of the wings but at the same time overcome too loose a connection. Each of the wings 14 and 15 is provided with upstanding edges or flanges 23 and 24 to reinforce the body portions 17 and 18 and make the wings rigid in construction but relatively light in weight. The wings are adapted to fold underneath the bottom of the base 11 and be totally concealed when the structure is not in use. Inasmuch as the shape and construction of the wings are such that some of the wings will overlap when folded, the wings 15 are provided with a pocket 25 into which the edges or corners 26 of the wings 14 are adapted to extend when the device is in folded position, Fig. 2.

The bosses 19 are provided with flat surfaces 27 and 28 against which a spring member 29 is adapted to engage. The spring member 29 comprises a longitudinal flat spring member 30 and a transverse flat spring member 31. Each member 30 and 31 is provided with a notch, which notches are complementary with each other and 55 permit the two portions to cross each other, as

indicated at 32, Fig. 3. The spring member 29 comprising the parts 30 and 31 is maintained in position by a boss or lug 33 which is preferably formed integral with the bottom of the member 11. This member 33 is provided with a cross slot 34 to receive the cross spring member 29. The spring member 29, comprising the cross leaves 30 and 31, presents an urging action against the straight or cam surfaces 27 and 28 and, therefore, tends to keep the wings 14 and 15 in either their closed or retracted position or in their open or extended position.

The invention provides a golf bag having a base member which is of the same relative contour as the bag, whether it be elongated or circular. The base member is provided with a plurality of protractable elements or extensions to support the bag in upright position when the elements or extensions are extended and which are adapted to be folded underneath the bag and concealed when the bag is to assume any other position but its upright one. Means are provided for maintaining the extensions in either extended or retracted position. The extensions are adapted to be in concealed or retracted position when the bag is being carried from one position to another but are adapted to be extended to form a bag support when it is desired to support the bag in its upright position.

The particular extensions are herein shown in the form of folding wings which are adapted to nest underneath the bottom plate of the bag support, and the means for maintaining the wings in either concealed or extended position comprises a spring member engaging cam surfaces on the bosses or knobs 19.

The invention therefore provides a simple, rugged construction, easily operated, for maintaining the bag in its proper upright position. The device is strong and durable in construction, free and easy in operation and economical to manufacture.

Changes may be made in the form, construction and arrangement of the parts without de-

parting from the spirit of the invention or sacrificing any of its advantages, and the right is hereby reserved to make all such changes as fairly fall within the scope of the following claims.

The invention is hereby claimed as follows:

1. A support for a golf bag comprising a plurality of manually operable flat wings of appreciable area pivotally mounted on the base of the golf bag near the periphery thereof and adapted to be folded manually and individually in closed position within the confines of the base or unfolded manually and individually to extend beyond the base to provide outwardly extending supporting legs for the bag, and spring means co-operating with each wing to lock resiliently each wing separately in either locked or unlocked position, some of said wings having pockets therein to receive a part of other of said wings.

2. A support for a golf bag comprising a plurality of manually operable wings pivotally mounted on the base near the periphery thereof and adapted to be folded manually and individually in closed position within the confines of the base or unfolded manually and individually to extend beyond the base to provide outwardly extending supporting legs for the bag, each of said wings being of appreciable thickness and having a wide flat under surface of substantial area arranged in substantially a single common plane to firmly and rigidly support the bag in upright position when the wings are unfolded, adjacent pairs of said wings when folded having portions received one above the other in overlapping relationship, the under side of alternate wings being provided with recessed pockets shaped to receive portions of the adjacent wings in said overlapping relationship, and upstanding reinforcing flanges on the upper edges of said wings, said flanges being cut away on alternate wings at portions of the wings adapted to be received within said recessed pockets when folded.

FRANK J. HEARNSHAW.
